UNITED STATES PATENT OFFICE

163,830

HOOK-ON INSTRUMENT FOR MEASURING A
VARIABLE CHARACTERISTIC IN AN ELECTRIC POWER CONDUCTOR

Edmund O. Schweitzer, Jr., Northbrook, Ill., assignor to E. O. Schweitzer Manufacturing Co., Inc., Northbrook, Ill., a corporation of Illinois

Application August 10, 1949, Serial No. 4,383

Term of patent 14 years

(Cl. D52—1)

To all whom it may concern:

Be it known that I, Edmund O. Schweitzer, Jr., a citizen of the United States, residing at Northbrook, in the county of Cook and State of Illinois, have invented a new, original, and ornamental Design for Hook-On Instrument for Measuring a Variable Characteristic in an Electric Power Conductor, of which the following is a specification, reference being had to the accompanying drawing, forming a part thereof.

Figure 1 is a top plan view of a hook-on instrument for measuring a variable characteristic in an electric power conductor, showing my new design.

Figure 2 is a view in side elevation of the instrument shown in Figure 1, both sides being identical except for the opposite positioning of the extensions at the right-hand end.

Figure 3 is a view, in front elevation, of the left-hand end of Figure 1.

Figure 4 is a view, in rear elevation, of the right-hand end of the instrument shown in Figure 1.

I claim:

The ornamental design for a hook-on instrument for measuring a variable characteristic in an electric power conductor, as shown and described.

EDMUND O. SCHWEITZER, JR.
